Edmund G. Hansen
ATTORNEY.

UNITED STATES PATENT OFFICE.

DANIEL G. ANDERSON, OF LOS ANGELES, CALIFORNIA.

EXTENSION LEAF FOR TABLES.

Application filed March 1, 1926. Serial No. 91,336.

This invention relates specifically to an extension leaf construction for tables having stationary tops, and is designed as an improvement on the construction illustrated 5 and described in my companion application entitled "Extension leaf construction for tables", bearing Serial Number 89,861, filed in the U. S. Patent Office February 23, 1926.

In the above mentioned application an extension leaf construction was illustrated and described as applied to a table provided with a stationary top having the characteristics of a table of the "library" or "davenport" type, that could be readily changed into a 15 table of a different type, when the concealed extension leaves were brought into operative position. The mechanism for operating the sliding extension leaves consisted of metal guide bars arranged in pairs secured to the 20 table top aprons, a member of the single pivoted leaf hinges slidingly engaging the metal guide bars, whereby the extension leaves could be slidingly chambered beneath the table top or withdrawn into an extended 25 position.

While the above construction operated in a satisfactory manner, yet the noise occasioned by the sliding of the metal hinge members or the metal guide rods was deemed 30 objectionable.

It is therefore an object of this invention to provide an extension leaf construction in which the mechanism for slidingly operating the extension leaves will practically be 35 noiseless in operation and positive in action.

The above objects are accomplished by means of the mechanism described in the following specification, reference being had to the accompanying drawings forming a part 40 thereof in which:

Fig. 1 is a perspective view of a table equipped with my extension leaves.

Fig. 1' is a perspective view of the top of the table with one of the leaves in an extended position and the other in a partially extended position.

Fig. 2 is an enlarged cross sectional view of a table top showing one leaf in an extended position, the companion leaf being 50 swung downwardly preparatory to chambering the same beneath the table top, and in dotted lines in a chambered or secured position, the view being taken on line 2—2 of Fig. 4.

Fig. 3 is an enlarged longitudinal section taken on line 3—3 of Fig. 2.

Fig. 4 is a bottom plan view of the table top equipped with the extension leaves, one leaf being in a closed, and the companion leaf in an extended position. 60

Fig. 5 is a detail sectional view showing one of the sliding supports for the leaves when extended.

Briefly, the invention herewith presented preferably consists of employing a library 65 table construction of a general well known type including an elongated table top provided on its under face adjacent its edges with downwardly extending "aprons". Secured to the under face of the top adjacent 70 its ends and midway between its sides are a pair of legs terminating in bases connected together with the usual brace. The outer edges of the extension leaves are of segmental form, and are hingedly connected to a plurality of slide members secured to the under 75 face of the table top, whereby the leaves when not in use may be quickly chambered beneath the top. Provision is made in the form of a double pivoted hinge in order that 80 the leaves may be drawn outwardly and around the depending aprons of the table top without interference.

In the drawings the extension leaf construction is illustrated in connection with a 85 table of the library or "davenport" type consisting of an elongated top 10, having a pair of supporting legs 11, 12, secured adjacent its ends, each leg having a base 13, the legs being connected with the usual ornamental 90 brace piece 13'. Secured to the under face of the table top adjacent its end and side edge are depending aprons 14, 15, 16 and 17, designed primarily to conceal from view the extension leaves when chambered or secured 95 below the table top, the aprons also serving to enhance the beauty of the table and to impart massiveness thereto.

As both extension leaves are exactly similar in construction and operate in the same 100 manner and for the purpose of brevity of description only one will be described herein.

The outer edge of the extension leaf 16 is of segmental form, but any other form that may seem desirable may be employed 105 without affecting its operation. Secured to the under surface of the table top are a plurality of cleats 18, arranged in triplicate adjacent the ends of the table to form a pair of grooved guide ways 19, 20, 21, 22, a pair 110 for each leaf. Mounted in the guide ways are slide bars 23, 24, 25, 26, the tongues 27

on the bars engaging the grooves in the guide ways. The extension leaves are secured to the slide bars at their outer ends by means of double pivoted hinges 28, each hinge consisting of an attaching member 29 rigidly secured to the outer face of the slide bars and at their outer ends, while a similar member 30, is secured to the under surface of the extension leaf 31 at its table meeting edge, the connecting member 32 of the hinge is of angular form and adapted when the leaf is in an extended position (see Fig. 2) to extend under and around the depending apron 14 of the table top.

In order to rigidly support the leaf 30 when in an extended position a slide bar 33 mounted in a grooved guide bar 34 is provided, the bar passing through an opening 35 formed in the apron 14, as best shown in Fig. 5, the outer end of the slide bar having a depending portion 36 designed to limit the inward movement of the bar when the leaf 30 is slid to its chambered position beneath the table top.

From the above description it is thought that the operation of extending the leaves will be clearly apparent. The leaves 30 when not in use are chambered beneath the table top, the inner ends of the leaves engaging oppositely disposed ledges 36', 37 secured to the table legs 11, 12, directly below the lower ends of the aprons for supporting the leaves in a position parallel to the under face of the top, see Figs. 2 and 4. When it is desired to extend the chambered leaves, each leaf 30 is pulled forwardly towards the operator until the outer ends of the slide bars

to which it is attached contacts with the inner vertical face of the apron 14. The leaf is now swung upwardly into engagement with the side or meeting edge of the table top and the supporting bar 33 is then pulled outwardly to support the leaf in an extended position, as shown in Figs. 2 and 4.

It will be observed from the above that no spring catches for holding the extension leaves in their chambered position beneath the table top, or operating chains or cables therefor are needed, and as the leaves are slidably mounted the operation of extending the leaves is considerably simplified.

What I claim is:

An extension table including a stationary table top, a leaf movable with relation to the table top and having an edge adapted to register with the table top edge, depending aprons secured to the table top around its edges, a pair of slide bars secured to the table top, and a pair of double pivoted hinges for the leaf, each hinge including a hinge member secured to one of the sliding bars, a second hinge member secured to the leaf adjacent to its table meeting edge and a third member bent into angular formation secured to the oppositely disposed first mentioned hinge members, the said hinge member adapted to extend under and around the depending apron of the table top, whereby the leaf may be slidably moved into and out of relation to the table top.

In witness that I claim the foregoing I have hereunto subscribed my name this 22nd day of January, 1926.

DANIEL G. ANDERSON.
